UNITED STATES PATENT OFFICE.

HARRY E. GOLDSTEIN, OF INDIANAPOLIS, INDIANA.

DESIGN FOR A CEILING PLATE FOR LIGHTING FIXTURES.

Application filed August 1, 1925. Serial No. 14,296. Term of patent 7 years.

To all whom it may concern:

Be it known that I, HARRY E. GOLDSTEIN, a citizen of the United States of America, a resident of the city of Indianapolis, county of Marion, and State of Indiana, have invented a new, original, and ornamental Design for a Ceiling Plate for Lighting Fixtures, of which the following is a specifica-

tion, reference being had to the accompanying drawings, forming a part thereof.

In the drawings, Figure 1 is a plan view, Fig. 2 is a side elevation.

I claim:

The ornamental design for a ceiling plate for lighting fixtures substantially as shown.

HARRY E. GOLDSTEIN.
